Primary Examiner — Catherine S Posthauer*Assistant Examiner* — Joan E. Diehl(74) *Attorney, Agent, or Firm* — Cantor Colburn LLP**CLAIM**

The ornamental design for a packaging for medical products, as shown and described.

DESCRIPTION

The patent or application file contains a least one drawing executed in color. Copies of this patent or patent application publication with color drawing(s) will be provided by the Office upon request and payment of the necessary fee.

FIG. 1 is a front isometric view of a packaging for medical products showing my new design;

FIG. 2 is a front elevation view thereof;

FIG. 3 is a rear elevation view thereof;

FIG. 4 is a right side elevation view thereof, the left side elevation view being identical; and,

FIG. 5 is a top plan view thereof, the bottom plan view being identical.

The broken lines are shown for the purpose of illustrating parts of the article which form no part of the claim.

**1 Claim, 3 Drawing Sheets
(2 of 3 Drawing Sheet(s) Filed in Color)**(56)
